RADIO RECEIVER OR THE LIKE

Raymond James Prohaska, New York, N.Y., assignor to
Electronic Instrument Co., Inc., Long Island City,
N.Y., a corporation of New York

Filed June 29, 1960, Ser. No. 61,147

Term of patent 7 years

(Cl. D56—4)

FIG. 1 is a front perspective view of a radio receiver or the like embodying my new design;

FIG. 2 is an enlarged side elevational view thereof;

FIG. 3 is an enlarged top plan view thereof;

FIG. 4 is an enlarged front elevational view thereof; and

FIG. 5 is an enlarged sectional view taken on the plane of line 5—5 in FIG. 4 and viewed in the direction indicated.

The dominant features of my design reside in the portions shown in full lines.

I claim:

The ornamental design for a radio receiver or the like, substantially as shown and described.
